UNITED STATES PATENT OFFICE

GEORGE H. JUNG, JR., OF CINCINNATI, OHIO, ASSIGNOR TO THE JUNG ARCH BRACE COMPANY, OF CINCINNATI, OHIO, A CORPORATION OF OHIO

ARCH SUPPORT

Application filed April 15, 1926. Serial No. 102,290.

This invention relates to a device for supporting the arches and muscles of the foot and has for an object the provision of a device of this kind which is easy of adjustment 5 to the particular needs of the individual wearer.

Another object is to provide a device of the kind wherein an adjustable pad is firmly retained in the desired position.

10 Another object is to provide a device of this kind which adapts itself to the contour of the foot to the end that the adjustable pad employed conforms more exactly to the orthopedic requirements.

15 Another object is to provide a device of this kind which is simple and economical of manufacture.

These and other objects are attained by the means described herein and disclosed 20 in the accompanying drawings, in which:

Fig. 1 is a side elevational view of a human foot having mounted thereon a brace of my invention.

Fig. 2, is a cross sectional view of the 25 brace taken on line 2—2 of Fig. 1.

Fig. 3, is a cross sectional view taken on line 3—3 of Fig. 2, and

Fig. 4, is an inverted plan view of the 30 device of my invention.

25 The device comprises a relatively wide band 6, of elastic webbing and preferably of such material as to be elastic only in the direction of its length and not in the direction of its width so that the band will not stretch longitudinally at the foot, but will yield to the movement of the foot muscles. The band 6 is formed by placing the ends 7 in abutment with one another and securing them by cross stitching 8 in order to provide the endless band. The seam thus formed is placed longitudinally along the center of a strip of fabric or tape 9 and the band 6 is secured to said tape 9 by longitudinal rows of stitching 10. The band 6 thus formed is now ready to be attached to the base and pad holding portion of the device, the construction of which will now be described.

30 A bottom member 11 is formed of comparatively stiff leather having a forward end 12 wide enough to be received in the

shoe of a wearer adjacent the ball of the foot. The rear end 13 is tapered off from each side of the forward end 12 in order to conform generally to the narrow part of the foot beneath the instep. It will be understood that the stiff leather members 11 are made separately for the right and left foot. A second or upper member 14 is shaped similarly to the bottom member 11 but is made of soft yieldable leather. The members 11 and 14 are joined together at the forward end 12 by a row of stitching 15 and at the rear by a transverse row of stitching 16. A layer of soft felt 17 is retained between the members 11 and 14 at the forward end 12 by cementing it to the lower member 11. The band 6 is secured to the upper face of the lower member 11 by cementing the fabric 9 thereto and then placing the upper soft leather member 14 over the band 6 and then sewing the parts together by stitches 16. A resilient pad 18 which may be of rubber or any other suitable material is then inserted in the pocket formed between the lower face of member 14 and the upper inner face of the band 6. The pad may be passed through the lateral opening at either side of the upper member 14. This pad 18 may be very readily adjusted as the orthopedic requirements demand. It should be noted that the soft felt 17 covers the forwardly disposed end of the strip of fabric 9 and may also receive a portion of the pad 18 so that the wearer will not be able to feel the edge 19 of the band 6 nor any of the other parts, all of these being perfectly cushioned by the felt 17. In the manufacture of the braces of my invention the stiff lower members 11 are first cut and the soft upper member 14 stitched thereto by the stitching 16. The band and strip of fabric are then made and the fabric strip 9 cemented to the lower member 11. The felt 17 is then positioned on the forward upward face of member 11 whereupon the band 6 may be turned inside out so as to dispose the main body thereof downwardly instead of as in the position shown, whereupon the final row of stitching 15 is completed after which the pad 18 may be inserted be-

tween that portion of web 6 disposed between the lower member 11 and the upper member 14.

When placed upon the foot of a wearer with the pad 18 properly positioned, the band 6 will take the shape of the foot of the wearer and lift the free lateral edges of the soft upper member 14 against the wearer's foot and at the same time will press the pad firmly against the foot, retaining it in such position as may be desired. It will be noted that inasmuch as the band 6 is secured to the lower member 11 it cannot slip laterally or rotate upon the foot of the wearer and that as the wearer moves the muscles of his foot in taking a step, the band will retain its proper position and also hold the pad 18 firmly against the proper part, thus allowing ample freedom of movement of the muscles of the foot and at the same time supporting those weakened or displaced parts as require artificial aid.

The pads 18 being easily inserted and removed may be readily replaced with larger or smaller pads and also pads of various shapes.

What I claim is:

1. In an arch brace the combination of a lower leather member and an upper leather member, rows of stitching for securing said members together at their opposite ends, an endless band of elastic material extending between the upper and lower leather members, a strip of fabric secured to the band by means of stitching, said strip extending for a distance beyond the lateral edges of said band and being also secured to the upper face of the lower leather member by adhesive means, the space between the endless band and the upper leather member being open at its sides and serving as a pocket for receiving an arch supporting pad.

2. An arch support comprising an endless elastic band, a fabric secured transversely of said band to provide a non-elastic portion in the band, and a leather member adhesively secured to the fabric.

3. In an arch support a stiff leather bottom, an endless elastic member, a strip of fabric sewed transversely across the band and adhesively secured to said bottom member, a top member secured at its opposite ends to the bottom member, padding means on the bottom member adjacent the band and a freely adjustable pad disposed between the band and the top member.

4. In an arch support, a strip of elastic webbing having its ends in abutment and stitched to provide a smooth endless band, and a fabric member covering the joined ends of the band and stitched thereto for providing a flat reinforced and non elastic portion transversely of the band and forming a means adapted for adhesive connection to a surface of a stiff material.

5. An arch support comprising an endless elastic band, means to render inelastic a narrow section of the band and a leather pad holding member adhesively attached to said means.

In testimony whereof, I have hereunto subscribed my name this 9th day of April, 1926.

GEORGE H. JUNG, JR.
